UNITED STATES PATENT OFFICE.

CHARLES R. LAMBERT, OF DETROIT, MICHIGAN, ASSIGNOR TO THE CLAYTON & LAMBERT MANUFACTURING COMPANY, OF DETROIT, MICHIGAN, A CORPORATION OF MICHIGAN.

DESIGN FOR A BLOW-TORCH.

50,557.

Specification for Design.

Patented Apr. 3, 1917.

Application filed March 8, 1916. Serial No. 82,933. Term of patent 14 years.

To all whom it may concern:

Be it known that I, CHARLES R. LAMBERT, a citizen of the United States of America, residing at Detroit, in the county of Wayne and State of Michigan, have invented a certain new, original, and ornamental Design for Blow-Torches, of which the following is a specification, reference being had thereto to the accompanying drawings, forming part thereof, in which the figure illustrates

a blow torch in side elevation, showing my new design.

I claim:

The ornamental design for a blow torch, substantially as shown.

CHARLES R. LAMBERT.

Witnesses:

JOHN E. LAMBERT,
JENNIE S. BUNTON.
